US00D879744S

(12) **United States Design Patent** (10) **Patent No.:** **US D879,744 S**
Hu (45) **Date of Patent:** **** Mar. 31, 2020**

(54) **EARPHONES**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/716,057**

(22) Filed: **Dec. 6, 2019**

(30) **Foreign Application Priority Data**

Jun. 27, 2019 (EM) 006599627-0002

(51) **LOC (12) Cl.** **14-01**

(52) **U.S. Cl.**

USPC **D14/206**

(58) **Field of Classification Search**

USPC D14/206, 205, 223; 181/129, 130, 135; 379/430, 431; 381/380, 381, 374;

Primary Examiner — Paula Allen Greene

(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 2; and,

FIG. 11 is an enlarged view of portion 11 shown in FIG. 4. In the drawing the claimed design is defined by the shaded surfaces, the broken lines depict environment that forms no part of the claimed design.

1 Claim, 11 Drawing Sheets
